Application October 8, 1956, Serial No. 614,405

8 Claims. (Cl. 1-3)

This invention relates to staplers and particularly to certain improvements in those staplers provided with a staple supporting rail, a hold-down member for said rail and forming therewith a staple magazine, and a staple pusher, and in which the retraction of the staple pusher causes the opening of the stapler parts to permit loading staples or to remove troubles which may have caused faulty operation.

In conventional staplers of the type described, the automatic opening, through retraction of the staple pusher, is accomplished by provision of a locking yoke on the staple supporting rail and a recess in the hold-down member in the region of the pivot, the yoke being coupled to move with the staple pusher against the direction of staple feed, so as to fall into the recess and permit the stapler parts to open automatically.

One disadvantage of these known arrangements is that the hold-down member which is pivotally connected to the staple supporting rail cannot be opened sufficiently to give free access to the entire length of the staple supporting rail in order to insert new staple wire sticks. Furthermore, only limited accessibility is possible to the parts of the stapling mechanism which effect the expulsion of the stapling wire. Another disadvantage of conventional staplers of this type is that they require an additional push spring system acting on the locking yoke which complicates the mechanism and increases its cost.

It is a primary object of this invention to provide a stapler so constructed as to obviate the above enumerated disadvantages of conventional construction.

It is a further object of the invention to provide a simply formed and attached device which normally locks the supporting rail to the hold-down member in closed position but which is released upon retraction of the staple pusher to permit automatic opening of the supporting rail and hold-down member, completely exposing the supporting rail for staple refilling purpose.

A further objective of the invention lies in the provision of an improved spring and support means therefor to separate the staple supporting rail, hold-down member and stapling arm to open position upon release of the above-mentioned locking device.

A still further object of the invention lies in the provision of a locking device formed of an extremely rigid, tiltable locking rail, which carries a locking wedge and is operated by the staple pusher, the locking rail being held and swingably mounted within the supporting rail without additional supporting parts.

Another objective of the invention lies in the provision of a stapler having an improved hinge spring constructed to hold the staple supporting rail to the base plate between flexible gripping jaws which permit ready engagement and disengagement of these parts, the hinge spring and base plate being so formed as to enable ready assembly without the need of additional fastening parts.

The novel features that are considered characteristic of the invention are set forth with particularity in the appended claims. The invention itself, however, both as

2

to its organization and its method of operation, together with additional objects and advantages thereof, will best be understood from the following description of specific embodiments when read in connection with the accompanying drawings, wherein like reference characters indicate like parts throughout the several figures and in which:

Fig. 1 is a side view of a stapler constructed according to the invention with the hold-down member in an open position and showing the portions in the region of the high pressure spring, the hinge spring and staple driving blade support in partial cross section;

Fig. 2 is a cross-sectional view of the stapler taken on line 2-2 of Fig. 1 and showing the interlocking arrangement between the staple supporting rail and base plate;

Fig. 3 is a bottom view of the hold-down member, staple supporting rail, staple feed and locking mechanism assembly, showing the hold-down member in closed position, certain of the parts being shown in section for clarity;

Fig. 4 is a cross-sectional view taken on line 4-4 of Fig. 3 and in inverted position corresponding to that of Fig. 3;

Fig. 5 is a bottom view similar to Fig. 3 but showing the assembly at the moment of release of the locking mechanism;

Fig. 6 is a bottom view similar to Fig. 3 but showing the hold-down member in opened position and the staple pusher in a completely retracted position held by the locking mechanism;

Fig. 7 is a cross-sectional view taken on line 7-7 of Fig. 6;

Fig. 8 is a section through the staple supporting rail and through the bearings of the locking rail, both in inverted position corresponding to the positions of Figs. 3-6 but with the locking rail shown in process of assembly before it snaps into engagement;

Fig. 9 is a section similar to Fig. 8 but showing the locking rail engaged;

Fig. 10 is a top view of the base plate of the stapler with its attached hinge spring;

Fig. 11 is a longitudinal section through the base plate of the stapler showing the attached hinge spring and taken on line 11-11 of Fig. 10;

Fig. 12 is a cross section of the base plate through the holding lug for the hinge spring taken on line 12-12 of Fig. 10;

Fig. 13 is a perspective view of a modified base plate and hinge spring assembly, and

Fig. 14 is a cross-sectional view taken on line 14-14 of Fig. 13.

Referring now to the drawings, specifically to Figs. 1 and 2, a stapler in accordance with the invention comprises a staple supporting rail 1, a hold-down member 2, a stapling arm 4 and a base plate 6 which are hingedly connected to each other by a pivot 5. The staple supporting rail 1 is an elongated channel member of inverted U-shaped cross section, upon which is seated a supply to staples, not shown. The hold-down member 2 extends over the staple supporting rail 1 and forms with said rail a staple magazine. The forward, inner face of the hold-down member 2 is shaped to cooperate with the end face of the supporting rail 1 to form a staple ejection passage. The stapling arm 4 covers the hold-down member 2 and is equipped, in the usual manner, with a staple driving blade 3 for individually ejecting each wire staple through said ejection passage against a die or matrix oppositely positioned on the base plate 6.

The stapling arm 4 is biased to a spread position with respect to the hold-down member 2 by a leaf spring 7. The leaf spring 7 passes intermediately through a slot

8 in, and bears against, the hold-down member 2 while its forward end bears against the stapling arm 4 and its rearward end, that is, the end next to the hinge 5, rests springingly on the staple supporting rail 1. Thus, the spring 7 effects a double function, namely, to spring upwardly both the stapling arm 4 and the hold-down member 2. The leaf spring 7 is held in fixed position in the assembly by a holding lug 9 on the hold-down member 2 seated in an aperture in said spring.

A staple pusher 10 is slidably arranged on the staple supporting rail 1 to push the staples forwardly toward their ejection position. A finger grip yoke 11 is fastened to the pusher 10 and passes under the supporting rail 1. The grip 11 is positioned below and extends outwardly of the hold-down member 2 so that by means thereof, the pusher 10 may be pulled back from the outside even when the hold-down member is closed. The staple pusher 10 is pressed forwardly in the direction of the staple ejection passage by a coil spring 12, Figs. 3, 5 and 7, and thereby effects the feed of the wire staples to their operating position.

Within the open bottomed channel of the staple supporting rail 1, is supported a tiltbeam-like locking member 13, as shown in Figs. 3-9. The member 13 is elongated and of inverted L-shaped cross section which, at its broadest part, completely spans the channel of the supporting rail 1. The base 13a of the locking member 13 is a flat element having curved sides and, in assembled position, bears against the inner face of the supporting rail 1, as best shown in Fig. 9. The downturned side flange portion 13b of the member 13 extends along that edge of the base 13a which has the longer radius of curvature and is likewise curved. At the forward end of the flange 13b is an outwardly projecting locking lug 14 which is wedge-shaped with the base of the wedge at the bottom.

The locking lug 14, in the region of the staple ejection passage and under the influence of a spring 18, projects through locking slits 15 and 16, respectively, Figs. 1 and 5, in the staple supporting rail 1 and the hold-down member 2, holding these parts together in their closed position (Fig. 3) against the action of the leaf spring 7. At the opposite end, the flange 13b is formed as an inwardly turned control cam 17 which lies in the path of movement of an upturned lug 11a on the grip yoke 11. When the grip yoke 11 is retracted toward its rear position, the lug 11a pushes against the flange 13b and cam 17, causing the member 13 to execute a tilting movement which withdraws the locking lug 14 from the locking slit 16 of the hold-down member 2 (Fig. 5) thereby opening the staple magazine.

After the grip yoke 11 passes by the control cam 17, the locking member 13, under the action of the closing spring 18, is again swung into its closed position (Fig. 6) so that the control cam 17 moves in front of the lug 11a and blocks the grip yoke 11 together with the staple pusher 10 from moving forwardly. When the hold-down member 2 is depressed, it bears against the slanted face of the locking lug 14 which is forced inwardly and then snaps outwardly into the locking slit 16 to hold the hold-down member 2 closed. The inward movement of the lug 14 causes a swinging movement of the locking member 13 and its control cam 17 to release the grip yoke 11 together with the staple pusher 10 under pressure of spring 12 for forward movement against the staples in the magazine.

The supporting of the locking member 13 in the staple supporting rail 1 is accomplished by provision of a positioning lug 19 and a depressed holding nose 20 projecting inwardly from opposite sides of the staple supporting rail 1. The locking member 13 is inserted in a slanted position below the holding nose 20 (Fig. 8) and, by depressing, engages with an opening 13c over the positioning lug 19 of the staple supporting rail. The lug 19

not only holds the locking member 13 assembled, but also serves as a fulcrum for its pivotal latching and unlatching movements.

The hinge spring 21, which is fastened to the base plate 6, holds the staple supporting rail 1 and the associated hold-down member 2 and stapling arm 4 in a spread position against the base plate 6. The hinge spring 21 comprises an elongated leaf spring, the rear end of which is bent upwardly. This end is slit in such a manner to form two upturned grip-tongue-like legs, which are springy in all directions, each having projecting support lugs 22 and 23 directed toward each other and a similar pair of resting lugs 24 and 25 spaced above lugs 22 and 23. The support lugs 22 and 23 serve the bottom edges of the staple supporting rail 1 as a springy support while the resting lugs 24 and 25 clamp into respective depressions 26 and 27 in the staple supporting rail 1. In this manner, the hinge spring 21 holds the staple supporting rail 1 against the base plate 6 in a detachably locked position yet permits resiliently opposed downward movement of the supporting rail under stapling pressure applied to the arm 4.

The base plate 6 has stamped therein an upwardly pressed table 28 and inwardly pressed lugs 29 and 30 which together form a guide into which the hinge spring 21 can be slidably inserted from the hinge side 5. Upon insertion, the hinge spring 21 rests with a cut-out over the fixation lug 31 on the table 28 by means of which it is secured against accidental longitudinal movement. The deflection of hinge spring 21 is limited in an upward direction by the guide lugs 29 and 30 and in a downward direction by the table 28 of the base plate.

A modified base plate and hinge spring assembly is shown in Figs. 13 and 14. Here, the hinge spring 21' is pushed through a stamped holding loop 33 on the underside of the stamped base plate 32 and is held in position by a fixation lug 34 which seats in an opening of the spring. In order to limit the deflection of the hinge spring 21' in a downward direction, the base plate 32 is provided with a tongue 35 which protrudes through the slit-like cut-out of the bent up leg of the hinge spring 21' and serves to support the lower edges of lugs 22 and 23 of the hinge spring 21' at the limit of their downward deflection.

It is readily apparent from the foregoing description that the stapler in accordance with the invention is easily operated. When used to staple objects together, the supporting rail 1 and hold-down member 2 are in closed position, held therein by locking lug 14. Each time pressure is applied to the stapling arm 4, the staple driving blade 3 presses down on the one wire staple at the forward end of the supporting rail 1, forces it through the papers or objects to be fastened and presses the ends of the staple together in the forming matrix on base 6. The hinge spring 21 and leaf spring 7 return the parts to ready position for the next fastening operation.

When it is desired to refill the staple supply on the supporting rail 1 or to correct a faulty operation, the grip 11 is merely retracted to the position shown in Figs. 1 and 6. This tilts the locking rail 13 and releases lug 14 thus allowing the hold-down member 2 to move to its open position under pressure of spring 7, giving access to the entire upper surface of the staple supporting rail 1. When the refill or repair is completed, it is only necessary to press the stapling arm 4 downwardly to return all of the parts to their operative positions with the hold-down member 2 closed over and latched to the supporting rail 1 by lug 14.

Although certain specific embodiments of the invention have been shown and described, it is obvious that many modifications thereof are possible. The invention, therefore, is not to be restricted except insofar as is necessitated by the prior art and by the spirit of the appended claims.

That which is claimed as new, is:

1. A stapler comprising a base, a staple supporting rail for supporting a supply of staples, a spring-pressed staple pusher on said supporting rail for urging the staples toward an ejection position, a hold-down member surrounding the upper portion of said supporting rail and forming therewith a staple magazine, a stapling arm over said hold-down member, a hinge pivotally holding said base, supporting rail, hold-down member and arm together at one end of the stapler, a hinge spring separating said base and supporting rail, a leaf spring separating said hold-down member, arm and supporting rail, a fulcrumed locking rail rockably supported within said supporting rail and having a wedge-shaped locking lug at one end for penetration of aligned slots in said supporting rail and hold-down member, the other end of said locking rail being formed with a cam engageable by said pusher to rock the locking rail and release the said locking lug upon retraction movement of said pusher toward the hinge to permit said leaf spring to move said hold-down member to an open position giving access to the entire staple magazine and upper surface of said supporting rail, and a spring in said supporting rail urging said locking rail to latching position with said locking rail cam in the path of said pusher to prevent forward movement of the pusher from its fully retracted position.

2. A stapler as defined in claim 1 wherein said pusher is provided with a fixed finger grip yoke extending below said supporting rail and projecting outwardly therefrom and from said hold-down member, said yoke having a flange positioned to bear against said locking rail cam so as to rock said locking rail on its fulcrum upon retraction of said yoke and pusher.

3. A stapler as defined in claim 2 wherein said pusher is spring-biased away from said stapler hinge and said wedge-shaped locking lug has a slant surface adapted to be cammed inwardly out of its latching position by depressing movement of said hold-down member whereby said locking rail and cam are rocked out of the path of said pusher yoke flange permitting movement of said pusher away from the stapler hinge under pressure of said pusher biasing spring.

4. The combination, for use in a stapler, of an elongated, inverted U-shaped cross section staple supporting rail pivoted to a hold-down member at one end and a staple pusher biased away from said pivoted end, with a locking mechanism comprising a fulcrumed locking rail tiltably supported within said supporting rail, a spring-biased locking lug on said locking rail adapted to enter aligned slots in said supporting rail and hold-down member, and a cam on said locking rail adapted to bear against said pusher upon retraction thereof to release said lug from said slots and block return of said pusher.

5. The combination defined in claim 4 wherein said locking rail comprises a flat base having curved side edges and a down-turned flange extending along one edge with an opening in said flange medially of its length, said supporting rail having a projection on one wall spaced from the web portion thereof and receiving the edge of the locking rail base therebetween, said supporting rail having an inwardly projecting fulcrum lug on the wall opposite said projection and removably engaged in said flange opening.

6. The combination, for use in a stapler, of a staple supporting rail, a hold-down member and a stapling arm pivoted together at one end, with a leaf spring biasing said supporting rail, hold-down member and arm apart, one end of said spring bearing against said supporting rail near said pivoted end, the other end of said spring bearing against said arm and said spring intermediate its ends passing through an opening in said hold-down member, said spring having an opening and said hold-down member having a lug fitting into said spring opening to prevent longitudinal movement thereof.

7. The combination, for use in a stapler, of a base, a staple supporting rail, and a hinge spring on said base and flexibly supporting said staple supporting rail, said base having a table formed thereon and side walls with inwardly projecting flanges, said spring having a flat portion slidably mounted between said table and flanges, said spring having an opening in said flat portion, an upwardly projecting lug on said base table and removably nested in said opening to prevent further longitudinal movement of said spring, said spring having two spaced upturned arms carrying two pairs of opposed, inwardly extending, flexible jaws releasably gripping and supporting said staple supporting rail.

8. The combination, for use in a stapler, of a base, a staple supporting rail, and a hinge spring on said base and flexibly supporting said staple supporting rail, said base having a loop stamped therefrom, said spring having a flat portion slidably mounted through said loop, said spring having two spaced upturned arms carrying two pairs of opposed, inwardly extending, flexible jaws for gripping and supporting said staple supporting rail, and a tongue on said base extending between said arms below the lowermost pair of jaws to limit downward movement of said hinge spring.
